Primary Examiner—Dominic Simone*(74) Attorney, Agent, or Firm*—Terence P. O'Brien(57) CLAIM

I claim the ornamental design for a vamp of a footwear article, as shown and described.

DESCRIPTION

FIG. 1 is an upper, side perspective view of a vamp of a footwear article; and,

FIG. 2 is a top view of the vamp of the footwear article of FIG. 1.

The ornamental design that is claimed is shown in solid lines in the drawings. The broken (dashed) lines shown in FIGS. 1 through 2 are included for the purpose of illustrating environmental elements only and form no part of the claimed design.
